UNITED STATES PATENT OFFICE

96,092

DESIGN FOR A FISH LURE

Oscar Christiansen, St. Paul, Minn.

Application April 6, 1935, Serial No. 56,246

Term of patent 3½ years

To all whom it may concern:

Be it known that I, Oscar Christiansen, a citizen of the United States, residing at St. Paul, in the county of Ramsey and State of Minnesota, have invented a new, original, and ornamental Design for a Fish Lure, of which the following is a specification, reference being had to the accompanying drawing, forming part thereof.

Fig. 1 is a top view, Fig. 2 a side elevation of Fig.

1, and Fig. 3 a front view, of a fish lure, showing my new design.

The cross hatching on the drawing indicates contrasting colors.

I claim:

The ornamental design for a fish lure, as shown and described.

OSCAR CHRISTIANSEN.
